LUMINAIRE LENS

Kurt Franck and Robert G. McPhail, Newark, Ohio, assignors to Holophane Company, Inc., New York, N. Y., a corporation of New York

Application January 3, 1957, Serial No. 44,391

Term of patent 14 years

(Cl. D48—16)

FIG. 1

Fig. 1 is a bottom perspective view of a luminaire lens, showing our new design;

Fig. 2 is a bottom view of the luminaire as illustrated in Fig. 1 with a portion omitted for convenience of illustration only;

Fig. 3 is a side view of the luminaire as illustrated in Fig. 1 with a portion omitted for convenience of illustration as in Figure 2;

Fig. 4 is a sectional view taken along line 4-4 of Fig. 2;

Fig. 5 is a sectional view taken along line 5-5 of Fig. 4; and

Fig. 6 is an enlarged detail view of the portion of Fig. 2 indicated at 6.

The several patterns which are only partially indicated in Figure 1 for convenience of illustration are repeated throughout the length and width of the luminaire as best disclosed in Figures 2 and 3.

We claim:

The ornamental design for a luminaire lens, as shown and described.
